(57) **CLAIM**

The ornamental design for a magnetic dry erase calendar whiteboard, as shown and described.

DESCRIPTION

FIG. 1 is a perspective view of a magnetic dry erase calendar whiteboard showing my new design;

FIG. 2 is a rear view thereof;

FIG. 3 is a front elevational view thereof;

FIG. 4 is a rear elevational view thereof;

FIG. 5 is a left side elevational view thereof;

FIG. 6 is a top plan view thereof;

FIG. 7 is a bottom plan view thereof; and,

FIG. 8 is an exploded perspective view thereof.

The broken lines in the drawings show portions of the magnetic dry erase calendar whiteboard that form no part of the claimed design.

The dash-dot-dash lines in the drawing displays a bracket indicating the scope of the explosion diagram in this design, which does not form part of the claimed design.
